INTERNAL COMBUSTION ENGINE

Oswald Schlaupitz, Canton, Ohio, assignor to The Timken Roller Bearing Company, Canton, Ohio, a corporation of Ohio

Application April 17, 1936, Serial No. 74,871

10 Claims. (CL 123—177)

This invention relates to internal combustion engines of the Diesel type, wherein the fuel injection nozzle extends through the cooling chamber of the engine cylinder and is cooled by the 5 cooling fluid in said chamber. The invention has for its principal object to provide for separating the nozzle from the cooling chamber when it is desired to remove the nozzle from the cylinder. Other objects are simplicity and cheapness of 10 construction, ease of operation and compactness of design. The invention consists in the construction, combinations and arrangements of parts hereinafter described and claimed.

In the accompanying drawing, which forms 15 part of this specification and wherein like symbols refer to like parts wherever they occur,

Fig. 1 is a fragmentary plan view of the fluid cooled cylinder of an internal combustion engine embodying my invention.

20 Fig. 2 is a vertical section on the line 2—2 in Fig. 1.

Fig. 3 is a horizontal section on the line 3—3 in Fig. 2, with the valve in position to permit flow of the cooling fluid to and around the injection 25 nozzle; and

Fig. 4 is a view similar to Fig. 3 with the valve in position to prevent the flow of the cooling fluid to said nozzle.

Referring to the accompanying drawing, my 30 invention is shown in connection with an internal combustion engine of the Diesel type, the upper portion only of a cylinder being shown. Said cylinder comprises inner and outer walls 1 and 2, respectively, that are spaced apart to form a 35 chamber or jacket 3 therebetween adapted to contain water or other suitable cooling medium. The inner and outer walls of the cylinder head have aligned openings 5 and 6, respectively, extending therethrough; and said walls are connected by a cylindrical wall or web 7, which is disposed concentric to said openings and forms a chamber 8 in the cooling chamber 3. The wall 1 of the smaller chamber 8 is provided with diametrically opposed openings 9 which permit the 45 cooling liquid in the main cooling chamber to flow through said smaller chamber.

The cylinder is provided with a valve 10 for cutting off communication between the main cooling chamber 3 and the smaller chamber 8 and for 50 manently closing the opening 6 in the outer wall 2 of said cylinder. Said cut-off valve comprises a cylindrical sleeve portion 11 rotatably mounted in the cylindrical chamber 8 and provided with diametrically opposed openings 12 adapted to be 55 brought into and out of register with the dia-

metrically opposed openings 9 in said wall of said chamber. The valve has a closed outer end provided with an outstanding flange 13 adapted to rest on the top of the cylinder head and is held down on said head by means of a pair of cap 5 screws 14 located one on each side of said valve. The cap screws 14 extend through arcuate slots 15 provided therefor in the top flange 13 of the valve and have their lower ends threaded into the outer wall of the cylinder head. The arcuate 10 slots 15 are disposed concentric to the rotary axis of the valve and are of sufficient length to permit the required oscillatory movement of the valve.

Fluid is injected into the combustion space 4 of the cylinder by means of a suitable injection 15 nozzle 16 having an exteriorly threaded portion that is threaded into a threaded hole 17 that extends through the outer end of the valve 10 in axial alignment with the hole 5 in the inner wall 1 of the cylinder head. The body portion of 20 said nozzle extends through the valve sleeve 11 centrally thereof with its inner or discharge end 18 tapered to cooperate with a tapered seat 19 provided therefor in the outer end of the opening 5 which extends through the inner wall of the 25 cylinder and opens into the compression space 4 thereof.

By the arrangement described, the beveled discharge end 18 of the fuel injector or nozzle 16 is forced tightly against the beveled seat 19 provided therefor in the opening 5 leading into the combustion space 20 of the cylinder by rotating the injector in the threaded opening 17 provided therefor in the outer end of the rotary valve 10 which controls the flow of the cooling fluid to and 30 around the said nozzle. When it is desired to remove the injection nozzle, the clamp screws 14 are loosened and the valve 10 rotated to bring the openings 12 therein out of register with the openings 9 in the cylindrical wall or valve seat 7, thereby cutting off communication between the main 35 cooling chamber and the valve chamber and thus permitting removal of said nozzle without discharge of the cooling fluid through the threaded opening 17 in the outer end of said valve. 40

45 What I claim is:

1. In an internal combustion engine, a cylinder having a cooling chamber, a fuel injector extending through said chamber into said cylinder, and a valve surrounding said injector for separating the same from said chamber. 50

2. In an internal combustion engine, a cylinder having a chamber adapted to contain a cooling fluid, a fuel injector extending through said chamber into said cylinder, and means for cut- 55

ting off the flow of the fluid in said chamber to said fuel injector.

3. In an internal combustion engine, a cylinder having a chamber containing a cooling fluid, a fuel injector extending through said chamber into said cylinder, and a valve for controlling the flow of the fluid in said chamber to said fuel injector.

4. In an internal combustion engine, a cylinder having a cooling chamber, a fuel injector extending into said cylinder through said chamber, and a valve surrounding said fuel injector and adapted to separate the same from said chamber, said valve constituting a support for said fuel injector.

5. In an internal combustion engine, a cylinder having a cooling chamber, a fuel injector extending into said cylinder through said chamber, a valve surrounding said fuel injector and adapted to separate the same from said chamber, said valve constituting a support for said fuel injector, and means for securing said valve to said cylinder, said means permitting limited rotary movement of said valve.

6. In an internal combustion engine, a cylinder having a main cooling chamber and a valve chamber communicating with said main cooling chamber, a valve in said valve chamber for controlling communication between said chambers, and a fuel injector removably mounted in said valve and extending into said valve chamber with its inner end in communication with the combustion space of said cylinder.

7. In an internal combustion engine, a cylinder having a main cooling chamber and a cylindrical valve chamber communicating with said main cooling chamber, a hollow cylindrical valve rotatable in said valve chamber for cutting off communication between said chambers and a fuel injector removably extending into said valve with its inner end in communication with the combustion space of said cylinder.

8. In an internal combustion engine, a cylinder having a main cooling chamber and a cylin-

drical valve chamber communicating with said main cooling chamber, a hollow cylindrical valve, rotatable in said valve chamber for cutting off communication between said chambers, a fuel injector removably extending into said valve with its inner end in communication with the combustion space of said cylinder, said valve being provided at its outer end with an outstanding flange, provided with arcuate openings, and fasteners extending through said openings into said cylinder.

9. In an internal combustion engine, a cylinder having spaced inner and outer walls forming a main cooling chamber therebetween said walls having aligned openings extending therethrough and being connected around said openings by a wall forming a cylindrical chamber communicating with said main chamber, a valve having a portion closing the opening in the outer wall of said cylinder and a hollow cylindrical portion rotatable in said cylindrical chamber for controlling communication between said chambers, and a fuel injector removably supported in an opening provided therefor in said valve with its discharge end in register with the opening in the inner wall of said cylinder.

10. In an internal combustion engine, a cylinder having spaced inner and outer walls forming a main cooling chamber therebetween said walls having aligned openings extending therethrough and being connected around said openings by a wall forming a cylindrical chamber communicating with said main chamber, a valve having a portion closing the opening in the outer wall of said cylinder and a hollow cylindrical portion rotatable in said cylindrical chamber for controlling communication between said chambers, and a fuel injector removably supported in an opening provided therefor in said valve with its discharge end in register with the opening in the inner wall of said cylinder, the cooperating portions of said inner wall opening and the discharge end of said fuel injector being beveled.

OSWALD SCHLAUPITZ.
